UNITED STATES PATENT OFFICE.

EDWARD R. BALES, OF CENTRALIA, ILLINOIS.

COMPOUND GAS-ENGINE.

SPECIFICATION forming part of Letters Patent No. 596,352, dated December 28, 1897.

Application filed October 24, 1896. Serial No. 609,871. (No model.)

To all whom it may concern:

Be it known that I, EDWARD R. BALES, of Centralia, in the county of Marion and State of Illinois, have invented a new and Improved 5 Compound Gas-Engine, of which the following is a full, clear, and exact description.

The object of the invention is to provide a new and improved compound gas or gasoline engine which is simple and durable in construction, very effective in operation, and arranged to utilize the motive agent to the fullest advantage, to reduce vibration to a minimum, and to run the engine with a comparatively small fly-wheel.

15 The invention consists of certain parts and details and combinations of the same, as will be fully described hereinafter and then pointed out in the claims.

Reference is to be had to the accompanying 20 drawings, forming a part of this specification, in which similar characters of reference indicate corresponding parts in all the figures.

Figure 1 is a sectional side elevation of the improvement. Fig. 2 is an enlarged cross-section of the same on the line 2 2 of Fig. 1. Fig. 3 is an enlarged face view of the variable eccentric, with the driving-shaft in section, on the line 3 3 in Fig. 1. Fig. 4 is a sectional plan view of the same with the driving-shaft 25 partly broken away, and Fig. 5 is a sectional face view of the cam for the primary exhaust-valve.

The improved compound gas-engine is provided with two high-pressure cylinders A and B, containing the pistons C and C', respectively, connected by pitmen C² C³, respectively, with the crank-arms D' D², respectively, secured on the main driving-shaft D and set at the same angle, so that the pistons 30 C and C' move in unison in their cylinders A and B. On the shaft D is also arranged a crank-arm D³, standing diametrically opposite to the crank-arms D' D² and connected by a pitman C⁴ with a piston C⁵, reciprocating 35 in a low-pressure cylinder E, arranged midway between the high-pressure cylinders A and B. The weight of the pistons C C' and their pitmen is approximately the same as that of the piston C⁵ and its pitman C⁴, so that 40 the engine is balanced to reduce vibrations to a minimum.

The high-pressure cylinders A and B are provided with the usual devices for filling the upper or working ends of the cylinders with explosive mixture and with igniting devices 55 for igniting the said mixture, and as these devices are well known I do not deem it necessary to show and describe the same in detail.

The working ends of the cylinders A and B are connected by exhaust-ports a and b with 60 the exhaust-chambers F and F', respectively, secured to the corresponding cylinders A and B and containing the primary exhaust-valves G and G' and the secondary exhaust-valves H and H', respectively. The primary exhaust-valves G and G' open into a pipe or tube I, forming a receiver, from which leads a cylinder I', adapted to connect by a port c with the working end of the low-pressure cylinder E. A valve J reciprocates in the cylinder I' to connect the said port c alternately with the cylinder I' and the exhaust I², leading to the atmosphere. The pipe I is also provided with a suction-valve I³ to allow air to pass into the pipe I to mix with the exhaust 75 from the high-pressure cylinders. The purpose of this suction-valve is to avoid the resistance which would be created by the vacuum in the receiver during the downward movement of the low-pressure piston when 80 the engine is started—that is, before an explosion occurs in either of the high-pressure cylinders.

The primary valves G and G' are adapted to open alternately, so that the main portions 85 of the exhausts from the high-pressure cylinders A and B are alternately discharged into the pipe I and the cylinder I', to pass from the latter into the low-pressure cylinder E and actuate the piston C⁵ therein at every revolution 90 of the shaft D. Thus as the high-pressure cylinders A and A' receive alternate impulses at every second revolution of the shaft D and the low-pressure cylinder receives an impulse at every revolution of the shaft D it 95 is evident that the latter is driven continuously by power from the cylinders. It is understood that the inlet and igniting devices for the high-pressure cylinders A and B are arranged to act alternately to produce the result above referred to. Each of the primary exhaust-valves G and G' commences to open 100

at the time the corresponding piston C or C' is nearly at the end of the impulse or down-stroke, and this valve remains open during about seven-eighths of the following upstroke 5 and then closes. The secondary exhaust-valves II and II' then commence to open at this period and are held open during the remaining one-eighth of the upstroke, so that the products of combustion still contained in 10 the working ends of the cylinders are discharged to the atmosphere.

It will be observed that the exhaust gases from the high-pressure cylinders are not discharged directly into the low-pressure cylinder, but pass first into the receiver I I', whose communication with the low-pressure piston is controlled by the valve J. The advantage of such a receiver having a valved connection with the high-pressure cylinder and another 15 valved connection with the low-pressure cylinder consists, first, in giving a more constant back pressure to the high-pressure cylinder during the time the exhaust-valve is open to the receiver; second, in engines where the 20 speed is regulated when necessary by the omission of explosions the use of the receiver will aid to give some continuity of power by the expansion in the low-pressure cylinder of gases remaining in the receiver.

30 It will further be observed that the valve J acts both as an inlet-valve and as an exhaust-valve for the low-pressure cylinder.

The object of providing secondary exhaust-valves is to discharge the combustion products into the atmosphere at the time they have practically completed their useful work—that is, when the high-pressure piston is nearly at the limit of its instroke and the low-pressure piston near the limit of its outstroke. It will 35 be understood that the gases in the receiver are under a predetermined pressure, and a corresponding pressure is required to open the exhaust-valves of the high-pressure cylinders. If, therefore, the secondary exhaust-valves 40 were omitted, there would remain in the working chamber of the high-pressure cylinder a gaseous residue under the same pressure that prevails in the receiver. The residue would of course interfere with the 45 drawing in of the succeeding charge of explosive mixture. To obviate this defect, the residue is discharged to the atmosphere by opening the secondary exhaust-valves, as described.

50 In order to hold the primary exhaust-valves G and G' to their seats while pressure is still in the exhaust-chambers F and F', I provide the said valves with pistons G² and G³, working in cylinders F² and F³, respectively, formed 55 in the chambers F and F'. The valves G and G' are exposed to the same pressure as the faces of the pistons, so that the valves remain seated if pressure is still in the chambers F and F'. The cylinders F² and F³ are provided 60 with vent-cocks K and K', respectively, so that the under sides of the pistons G² and G³

are exposed to the atmosphere, the vent-cocks producing a dash-pot action for the pistons upon their downward movement—that is, at the time the valves G and G' are in the act of seating themselves.

The valve-stems G⁴ and G⁵ for the primary exhaust-valves G and G' are pivotally connected with cross-heads G⁶ and G⁷, respectively, fitted to slide in suitable bearings L and L', secured to the high-pressure cylinders A and B. The cross-heads G⁶ and G⁷ are spring-pressed and carry at their lower ends friction-rollers G⁸ and G⁹ in peripheral contact with cams N and N', formed on gear-wheels N² and N³, respectively, journaled in suitable bearings on the engine-frame and in mesh with pinions O and O' on the main driving-shaft D. The secondary exhaust-valves II and II' have their stems II² and II³ connected with spring-pressed cross-heads II⁴ and II⁵, respectively, likewise fitted to slide in the bearings L and L', previously mentioned. The cross-heads II⁴ and II⁵ carry friction-rollers II⁶ and II⁷ in peripheral contact with the cams N⁴ and N⁵, respectively, secured or formed on the gear-wheels N² and N³ on opposite faces from that on which the cams N and N' are located.

The cams N and N' serve to open and hold 95 open the primary exhaust-valves G and G' during the time previously specified to cause the exhaust from the high-pressure cylinders to pass into the receiver formed by the pipe I and the cylinder I', and hence to the port c 100 and low-pressure cylinder E, for the purpose above set forth. As soon as the friction-rollers G⁸ and G⁹ drop off the ends of the projections of the cams then the springs of the cross-heads G⁶ and G⁷ cause the primary exhaust-valves to close instantly, and at this time the secondary exhaust-valves II and II' are 105 opened by the projections on the cams N⁴ and N⁵ raising the cross-heads II⁴ and II⁵, and consequently opening the said valves. The 110 valves II and II' remain open but a short time—that is, about one-eighth of the return stroke, as previously mentioned—to permit the products of combustion remaining in the 115 working ends of the cylinders to pass through the ports a and b into the exhaust-chambers F and F' and from the latter through the open valves II and II' and the exhaust-outlets F⁴ and F⁵ to the atmosphere.

The valve J has its valve-stem J' connected 120 with a cross-head J², pivotally connected with the eccentric-head P² of an eccentric-strap P, engaged by a disk P², fitted to slide transversely on a wheel Q, secured to the driving-shaft D. Various means may be employed 125 to shift the eccentric-disk P² transversely on the said wheel Q for increasing or diminishing the throw of the eccentric, so as to regulate or cut off the valve J.

As shown in the drawings, the disk P² is 130 pivotally connected by one end of a bell-crank lever R, fulcrumed in the wheel Q and con-

nected by a link R' with a shifting collar R^2 , mounted to turn with and slide on the main shaft D . A shifting lever connects with the collar R^2 to move the same longitudinally on the shaft D and regulate the throw of the eccentric for the purpose previously described.

It is evident that by the arrangement described a continuous impulse is given to the shaft D for rotating the same while the engine is at work, so that the motive agent is utilized to the fullest advantage, and it requires but a light fly-wheel on the shaft D , and the vibrations of the engine are diminished to a minimum, owing to the complete counterbalancing of the parts above mentioned.

It is evident that for different makes of engines different mechanism may be employed, and hence I do not limit myself to the precise construction of the engine shown and described.

It is also evident that the engine can be run at a comparatively low rate of speed without danger of stopping, as is the case with simple gas-engines or unless four cylinders are provided.

Having thus fully described my invention, I claim as new and desire to secure by Letters Patent—

1. A compound explosive-engine, comprising two high-pressure cylinders provided with exhaust-valves, the working strokes of one high-pressure piston alternating with those of the other, a receiver into which is discharged the exhaust from said high-pressure cylinders, a low-pressure cylinder, and a valve controlling the communication of said low-pressure cylinder with the receiver in such a manner that the low-pressure cylinder is driven alternately by the exhaust-gases from the high-pressure cylinders, said valve when closing the low-pressure cylinder to the receiver, establishing a communication between said cylinder and an exhaust-port, substantially as described.

2. A compound explosive-engine, comprising a high-pressure cylinder, a low-pressure cylinder having a port adapted to serve as an inlet-port and as an exhaust-port as well, a connection between the exhaust-port of the high-pressure cylinder and the port of the low-pressure cylinder, and a valve located in said connection and arranged to alternately establish a communication from said port of the low-pressure cylinder to the said connection and to the exhaust, substantially as described.

3. A compound gas-engine, comprising two four-period high-pressure cylinders, each having a primary and a secondary exhaust-valve actuated successively, the secondary exhaust-valves discharging into the atmosphere, a receiver connected to the primary exhaust-valves, a low-pressure cylinder having a valved connection with the said receiver and

supplied with its motive agent therefrom, and means for opening and closing the sets of primary and secondary exhaust-valves for the two cylinders alternately, said means being timed to open the secondary exhaust-valves during the last portion of the exhaust strokes, as set forth.

4. A compound gas-engine, comprising two four-period high-pressure cylinders having their pistons moving in unison, a main shaft connected with the said pistons, an exhaust-chamber for each cylinder, each chamber containing successively-operating primary and secondary exhaust-valves, of which the latter open to the atmosphere, the said valves of the two high-pressure cylinders operating successively on alternate strokes of the said piston in the high-pressure cylinders, a receiver connected to the primary exhaust-valves, a low-pressure cylinder having a piston operating in opposite directions to the pistons in the high-pressure cylinders, and a valved connection controlled from the said shaft, for connecting the said receiver with the working end of the said low-pressure cylinder, substantially as shown and described.

5. A compound gas-engine, comprising two four-period high-pressure cylinders having their pistons moving in unison, a main shaft connected with the said pistons, an exhaust-chamber for each cylinder, each chamber containing successively-operating primary and secondary exhaust-valves, of which the latter open to the atmosphere, the said valves of the two high-pressure cylinders operating successively on alternate strokes of the said piston in the high-pressure cylinders, a receiver connected to the primary exhaust-valves, a low-pressure cylinder having a piston operating in opposite directions to the pistons in the high-pressure cylinders, a valved connection controlled from the said shaft for connecting the said receiver with the working end of the said low-pressure cylinder, and means for actuating the said primary and secondary exhaust-valves from the shaft, as set forth.

6. A compound explosive-engine, comprising a high-pressure cylinder provided with a main exhaust-valve, a low-pressure cylinder, a connection from the said exhaust-valve to the low-pressure cylinder, whereby the exhaust from the high-pressure cylinder will be delivered mainly to the low-pressure cylinder, a supplementary exhaust-valve whereby the remainder of the combustion products may escape from the high-pressure cylinder directly, and valve-operating mechanism timed to open the supplementary exhaust-valve during the last part of the exhaust stroke, substantially as described.

7. A compound explosive-engine, comprising a high-pressure cylinder provided with an exhaust-valve, a receiver into which is discharged the exhaust from said high-pressure

cylinder, a low-pressure cylinder having a valve-controlled connection with the receiver, a supplementary exhaust-valve whereby the remainder of the combustion products may escape directly from the high-pressure cylinder without passing into the receiver, and valve-operating mechanism timed to open the

supplementary exhaust-valve during the last part of the exhaust stroke, substantially as described.
